UNITED STATES PATENT OFFICE

MICHAEL KIWAD, OF NEW YORK, AND SAM THAU, OF BROOKLYN, NEW YORK,
ASSIGNORS TO METROPOLITAN LAMP CO. INC., OF NEW YORK, N. Y., A CORPORATION
OF NEW YORK

DESIGN FOR A COMBINED LIGHTING FIXTURE AND STAND

Application filed June 17, 1929. Serial No. 31,739. Term of patent 3½ years.

To all whom it may concern:

Be it known that we, MICHAEL KIWAD and SAM THAU, both citizens of the United States of America, residing in the city, county, and State of New York, and in the borough of Brooklyn, county of Kings, city and State of New York, respectively, have invented a new, original, and ornamental Design for Combined Lighting Fixture and Stand, of which the following is a specification, reference being had to the accompanying drawings, forming a part thereof.

Fig. 1 shows a front perspective view of the combined lighting fixture and stand which embodies our design. Fig. 2 is a side view. The dominant feature of the design is the center portion, together with the pedestals for the side lights.

We claim:

The ornamental design for a combined lighting fixture and stand substantially as shown and described.

MICHAEL KIWAD.
SAM THAU.
